Patented Dec. 16, 1924.

UNITED STATES PATENT OFFICE.

ORRIN B. POWELL, OF JACKSONVILLE, FLORIDA, ASSIGNOR TO LUCIAN B. POWELL,
JR., OF FARMVILLE, VIRGINIA.

RAILROAD SPIKE.

Application filed November 24, 1922. Serial No. 602,925.

To all whom it may concern:

Be it known that ORRIN B. POWELL, a citizen of the United States, residing at Jacksonville, in the county of Duval and State of Florida, has invented certain new and useful Improvements in Railroad Spikes, of which the following is a specification.

The object of the invention is to provide a simple and efficient form of spike particularly adapted for use in securing railway track rails to the ties under conditions which will prevent the pulling or drawing of the same by the upward strain applied to the rails and therefore imposed upon the portion 15 of the spike head which is arranged in overlapping relation with the rail base, and which will at the same time resist lateral strain due to a spreading tendency of the rails, but which may still be withdrawn from 20 the ties or extracted when required or when it is necessary to replace or repair rails or ties, by applying to the spike a strain which is different from that imposed thereon by the rail; a further object is to prevent break- 25 age of the shank immediate under the head, as often occurs with the spikes now in use. With these general objects in view the invention consists in a construction and combination of parts of which a preferred embodiment is shown in the accompanying 30 drawing, wherein:

Fig. 1 is a side view of a spike arranged in its operative position and showing in connection therewith and in section a rail and 35 a portion of a tie, part of which is also shown in section, to which the rail is secured by means of the spike, and also showing in connection therewith and in dotted lines the position of a pinch bar or similar 40 tool applied in the position necessary to draw the spike.

Fig. 2 is a rear view of the spike.

Fig. 3 is a bottom view of same.

The spike consists essentially of a shank 45 10 of which the body portion is increased in width from front to rear or from inner to outer surface toward its lower end and which is provided at its upper end with an enlargement 11 preferably having a back or 50 outer surface which is substantially in the plane of the corresponding surface of the body portion of the shank and with a front or inner surface which is obliquely disposed to the corresponding surface of the body 55 portion of the shank and is inclined inward-

ly from the angle 12 formed by the intersection of its inner or front surface with that of the body portion of the shank to provide what may for convenience be regarded as and termed a bevel or cam shoulder forming an obtuse angle with the direction of driving progress of the spike, said enlargement of the shank terminating in a longitudinally and transversely extended head 13, and the body portion of the shank terminating at its inner end with a sharp or abruptly reduced point 14. The spike shank is of substantially uniform thickness measuring from side to side or in a plane parallel with the inner and outer or front and rear surfaces thereof and the point is formed by beveling two sides only, as clearly shown in Fig. 1, and at the base of the point or substantially opposite the junction of the point proper with the body portion of the shank 70 is arranged an upwardly and outwardly directed barb 15 projecting outwardly beyond the inner or front face of the shank and serving as a means for positively engaging the fibre or material of the tie into which the spike is driven so as to effectively resist any tendency to draw or upwardly displace the spike particularly by an upward strain applied to the inwardly directed nose portion 13^a of the spike, which as indicated in the drawing is designed to overhang or overlap 80 and bear upon the base of the rail which is shown at 16. Obviously an upward strain upon the nose portion 13^a of the spike head will tend to draw the lower end of the shank 90 inwardly and thereby emphasize the resistance which is offered by the barb 15 to any drawing or extracting movement of the spike.

On the other hand the head is also extended outwardly or rearwardly to form a shoulder 13^b which in the normal position of the spike rests upon the surface of the tie indicated at 17, and by inserting a pinch bar or similar prying or lever constituting tool, 95 such as that shown for example in dotted lines at 18, beneath the shoulder 13^b it is possible to extract the spike from the tie by reason of the fact that an upward and inward strain applied by such a tool to the outer portion of the head of the spike tends to swing the lower end of the shank outwardly and thus reduce the resistance offered by the barb 15 to an extent sufficient to permit 105 of such extraction.

In driving the spike the inner or front face thereof is arranged in contact with the edge of the rail base or foot so that said face serves as a guide in directing the spike and 5 obviously when the spike has been driven sufficiently to bring the angle 12 into contact with the rail base the further driving movement results in an outward or rearward crowding of the spike by reason of the contact of the cam or bevel surface of the enlargement 11 with the rail base, and depending from the upper portion of the enlargement 10 at the outer or rear side of the spike is a second barb 19 inclined rearward toward its lower end at an inclination substantially corresponding with that of the inner or front face of the enlargement 11 so that as the final driving movement of the spike is conducted with the cam or bevel face 15 of the enlargement in contact with the rail base the spike is moved in a direction substantially parallel with the length of the barb 19 until the shoulder formed by the rear nose 13^b of the head comes in contact with the surface of the tie. This rearwardly and 20 downwardly directed barb thus serves as a brace to the fully driven spike to resist any tendency of the spike to move outwardly due to strains, for example, those caused by 25 the wheels of the rolling stock and which in ordinary practice result in the spreading of the rails and the consequent derailment of the cars.

It will be seen that the barb 19, however, 30 does not interfere with the drawing of the spike by the means and in the direction hereinbefore indicated for the reason that the drawing movement of the spike as described is substantially in the direction of the length of said barb and is accompanied by an inward or forward movement of the upper end of the spike which, as previously indicated, serves to effect the reduction in the resistance to withdrawal offered by the 35 upwardly directed barb with which the lower end of the shank is provided. Thus while the downwardly and rearwardly directed head barb 19 serves to resist outward strains applied to the spike or any tendency to displacement of the spike by reason of strains applied to the inwardly extending nose portion 13^a of the spike head, just as the point barb 15 serves to resist drawing or pulling strains applied to the head through the 40 agency of the rail base engaged thereby, both of said barbs are rendered ineffective in resisting an effort to withdraw the spike when the strain is applied to the outer nose end of the spike head under the conditions and by 45 the means above indicated for that purpose.

Having described the invention, what is claimed as new and useful is:

1. A rail spike having a shank provided with a terminal point having an upwardly and outwardly directed barb and a head hav-

ing an outwardly extended nose for overlapping engagement with a rail base, the shank being increased in width toward its lower end.

2. A rail spike having a shank provided with a terminal point having an upwardly and outwardly directed barb and a head having an outwardly extended nose for overlapping engagement with a rail base, the shank being increased in width towards its lower end and having an enlarged upper end 75 adjacent to the head.

3. A rail spike having a shank provided with a terminal point having an upwardly and outwardly directed barb and a head having an outwardly extended nose for overlapping engagement with a rail base, the shank being increased in width towards its lower end and having an enlarged upper end 80 with a cam face or beveled inner surface.

4. A rail spike having a shank provided with a terminal point having an upwardly and outwardly directed barb and a head having an outwardly extended nose for overlapping engagement with a rail base, the shank being increased in width in opposite directions from an intermediate point toward its extremities.

5. A rail spike having a shank provided with a terminal point having an upwardly and outwardly directed barb and a head having an outwardly extended nose for overlapping engagement with a rail base, the shank being provided at its enlarged upper end and at its outer side with an outwardly and downwardly inclined barb.

6. A rail spike having a shank provided with a terminal point having an upwardly and outwardly directed barb and a head having an outwardly extended nose for overlapping engagement with a rail base, the shank being provided at its enlarged upper end and at its outer side with an outwardly and downwardly inclined barb and having the inner face of said enlargement disposed 100 in an upwardly and inwardly inclined plane to the driving direction of the shank.

7. A rail spike having a shank provided with a terminal point having an upwardly and outwardly directed barb and a head having an outwardly extended nose for overlapping engagement with a rail base, the portion of the shank adjacent to the head being enlarged to form an upwardly and inwardly inclined cam or bevel face and being provided at its outer side with a downwardly inclined barb.

In testimony whereof, ORRIN B. POWELL has signed his name to this specification in the presence of two subscribing witnesses, this 16th day of May, 1922.

ORRIN B. POWELL.
